GRINDING MACHINE GUIDE BLOCK

Joseph Sunnen, Kirkwood, Mo.

Application October 29, 1932. Serial No. 640,271

7 Claims. (Cl. 51—184.1)

My invention has relation to improvements in engine cylinder grinding machines and it consists in the novel features of construction more fully set forth in the specification and pointed out in the claims.

The present invention is directed more particularly to the guide elements of a grinding machine of the type shown in my co-pending application, Serial No. 233,788, filed November 17, 1927, and is an improvement over the guide blocks forming the subject-matter of my application, Serial No. 608,373, filed April 30, 1932.

In the guide block of the last mentioned application the blocks are resiliently mounted on the ends of supporting elements carried by the carrier of the grinding machine, the arrangement being such that under the pressure imposed on the blocks in operation they are capable of yielding in a rectilinear direction. Furthermore, the blocks are pressed outwardly toward the cylinder wall by means of a spring at each end of the block and it is possible in operation for either end of the block to yield or move inwardly without any movement at the opposite end of the block.

It is the object of the present invention to so mount the blocks on their supports that angular or rotatory movement will be imparted to them under excessive pressure instead of rectilinear movement, and that when the blocks are so moved the cumulative pressure exerted by the springs at both ends will serve to oppose and resist the movement so that the block is incapable of yielding at one end only.

It is the further object of the present invention to simplify the construction of the guide block by eliminating from the guide block assembly the carriers or holders for the blocks. In the present construction the blocks are carried directly by the racks which serve as the supports, from the ends of which they are securely although yieldingly supported. These advantages, together with others inherent in the invention, will be better apparent from a detailed description of the same in connection with the accompanying drawing, in which:

Figure 1 is a side elevation of a grinding machine provided with my improved guide elements, part of said machine being broken away; Fig. 2 is a horizontal cross-section through the machine taken on the line 2—2 of Fig. 1; Fig. 3 is an elevation of one of the guide elements looking at the working face thereof; Fig. 4 is a longitudinal section through the guide element taken on the line 4—4 of Fig. 3; and Fig. 5 is an enlarged

cross-sectional detail taken on the line 5—5 of Fig. 3.

Referring to the drawing, 1 represents the tool holder of a Sunnen cylinder grinder of the type described in the above referred to patent application, said holder being suspended by a yoke 2 and collar 3 from a drive shaft 4. The collar 3 is pivotally connected to the holder 1 by means of studs 5, 5, and the yoke 2 is pivotally connected to the collar by means of studs 6, 6 so that a universal joint connection is formed between the shaft 4 and the holder 1. The holder 1 is provided with a longitudinally disposed axial bore 7 within which is housed a pinion shaft 8 rotatable by means of the adjusting head 9 for the purpose of extending and retracting abrasive elements 10, 10 and guide elements 11, 11 comprising the tools carried by the holder. The construction and the operation of the tool holder, comprising the parts just described, is substantially the same as that of the holder of my honing device described in detail in the aforesaid patent application and will not be further described herein except insofar as necessary to explain the operation of the guide elements 11, 11.

The guide elements 11, 11 comprise an angle-shaped block 12 carried on the outer ends of rack bar 13 which form the support for the block, said racks being slidably mounted in transverse bores 14, 14 intersecting with the axial bore 7 so that the teeth *t* of the racks will mesh with the elongated pinion 8. The outer end of each rack bar 13 terminates in successively reduced portions 15 and 16, the reduced portion 15 passing through an opening 17 in what may be termed the base 18 of the guide block, while the reduced portion 16 passes through an opening 19 in a retaining strip 20, over which the extremity of said reduced portion 16 is riveted. Thus the retaining strip 20 is firmly fixed to the rack bar 13 in spaced relation with the shoulder *s* formed by the reduced portion or stem 15. It will be observed that the length of the stem 15 is greater than the thickness of the base portion 18 of the block so that space is provided between the inner surface 18' of the block and the shoulder *s* for a spring 21 in the shape of a concavo-convex washer or perforated disk. The spring washers 21 exert their influence to hold the block 12 outwardly in contact with the retaining strip 20 and possess sufficient tension to hold the working surface 22 of the guide block firmly against the cylinder wall C when the grinding machine is in operation. However, when pressure is brought to bear against the working face 22 of the guide block due to

the vibrations of the machine in operation the spring washers 21 will yield, becoming flattened (as shown in Fig. 5) and allow the block 12 to be tilted or rotated rearwardly with respect to 5 the direction of rotation of the machine. Obviously, the compression of the springs 21, 21 increases the pressure with which the guide block bears against the cylinder wall, which pressure amounts to approximately twenty pounds on each 10 spring, or a total of forty pounds when the blocks 12 are rotated backwardly their maximum amount, that is, when the springs 21, 21 are completely compressed.

As explained in my pending application, Serial 15 No. 607,373, best results are obtained from the grinder when a free clearance of approximately .015" is maintained between the working faces 22, 22 of the guide blocks and the cylinder wall. However, it is impossible in practical operations 20 to maintain this clearance at any definitely fixed point and clearance is often reduced during the grinding operation. With my improved guide blocks an inward movement of approximately .020" may be obtained on each block by compressing 25 springs 21 so that it is possible to obtain a total relative movement between the blocks and the cylinder wall of approximately .035". Obviously, after the free clearance of .015" has been taken up any further relative movement between 30 block and cylinder wall will exert uniformly increasing pressure on the blocks. This increased pressure between the blocks and the cylinder wall will cause the face 22 of the blocks to wear more rapidly, thus gradually increasing the clearance 35 between the blocks and wall until the normal operating clearance is again obtained. Thus the blocks may properly be said to be self adjusting with respect to the amount of clearance between them and the cylinder wall.

40 It will be observed (Fig. 3) that the working face 22 of the block 12 is reduced in area at its medial portion 22'. As there is a tendency for the blocks to wear more rapidly toward the ends due to the instability with which the grinding 45 machine is held by the operator this reduction in area of the working face counteracts this tendency so that the entire working face of the block will wear off substantially uniformly.

As in my application, Serial No. 608,373, afore- 50 said, the block 12 is composed of a material that is relatively non-abrasive as it must not score the cylinder wall as it is rotated thereover. In addition to this property it should also be comparatively friable so that when the pressure of 55 the block against the cylinder wall C becomes greater than normal due to a decrease in the clearance between the block and the cylinder wall the working face 22 of the block will wear off with sufficient rapidity to quickly restore the 60 normal pressure. I have found that one material

possessing these properties is die cast metal containing zinc, copper and aluminum.

Having described my invention, I claim:

1. A guide element for cylinder grinding machines comprising an elongated block adapted 80 for contact with the cylinder, supporting elements for said block, said supporting elements having yielding connection with the block adjacent to the ends thereof, and the block being rotatable, relative to the supporting elements. 85

2. A guide element for cylinder grinding machines comprising a guide block adapted for contact with the cylinder, supporting elements for said block, said block having rotatable connection with said supporting elements. 90

3. A guide element for cylinder grinding machines comprising a guide block adapted for contact with the cylinder, supporting elements for said block, said block being yieldingly and tiltably carried by said supporting elements. 95

4. A guide element for cylinder grinding machines comprising a guide block adapted for contact with the cylinder, said block having a laterally extending base, and the ends of said base having yielding and tiltable connection with the 100 ends of the supporting elements.

5. A guide element for cylinder grinding machines comprising a guide block adapted for contact with the cylinder, said guide block having a base component and a cylinder contacting 105 component, suitable supporting elements for the block, and means on the ends of the supporting elements for securing the base component of the block thereto, and springs associated with the securing means effecting a yielding connection 110 between the supporting elements and the blocks.

6. A guide element for cylinder grinding machines comprising a guide block adapted for contact with the cylinder, said guide block having a base component and a cylinder contacting component, suitable supporting elements for the block, and means on the ends of the supporting 115 elements for connection with the base component of the block and a spring washer between each supporting element and the block for imposing 120 tension on said block.

7. A guide element for cylinder grinding machines comprising a guide block having a base component and a cylinder contacting component, supporting elements for the block, a stem at the 125 end of each supporting element and traversing an opening in the base component of the block, a retaining strip between the outer face of the base component and the ends of the stems of the supporting elements, and spring washers 130 disposed between the inner face of the base component and supporting elements.
